UNITED STATES PATENT OFFICE

119,654

DESIGN FOR A MOCCASIN

Samuel H. Chedekel, Lowell, Mass.

Application September 20, 1939, Serial No. 87,305

Term of patent 14 years

To all whom it may concern:

Be it known that I, Samuel H. Chedekel, a citizen of the United States, residing at Lowell, in the county of Middlesex and State of Massachusetts, have invented a new, original, and ornamental Design for a Moccasin, of which the following is a specification, reference being had to the accompanying drawing, forming part thereof.

Fig. 1 is a plan view of a moccasin showing my new design;

Fig. 2 is a front elevational view; and
Fig. 3 is a front perspective view thereof, on a slightly enlarged scale in comparison with the disclosures in Figs. 1 and 2.

I claim:

The ornamental design for a moccasin, substantially as shown.

SAMUEL H. CHEDEKEL.
